UNITED STATES PATENT OFFICE.

HULDA E. MIKAELSON, OF CHICAGO, ILLINOIS, ASSIGNOR OF ONE-HALF TO ANDERS NELSON, OF CHICAGO, ILLINOIS.

HAIR-CURLING DEVICE.

Application filed May 7, 1923. Serial No. 637,064.

To all whom it may concern:

Be it known that I, HULDA E. MIKAELSON, a citizen of the United States, and a resident of the city of Chicago, county of Cook, and State of Illinois, have invented certain new and useful Improvements in Hair-Curling Devices, of which the following is a specification.

This invention relates to hair curling devices and has for its object the provision of a device of this character including rollers adapted to be disposed on opposite sides of a strand of hair and having intermeshing portions adapted when heated to impart a wave or undulation to the strand of hair.

Another object of the invention is to provide mechanism to be used in conjunction with said rollers and so arranged as to impart a step by step movement to said rollers along the strand of hair.

Still another object of the invention is to provide means for moving the rollers apart for the purpose of placing a strand of hair therebetween, said rollers being normally resiliently pressed to engaging position.

And still another object of the invention is to provide electrical means for heating the rollers at all times and in various positions.

Other objects will appear hereinafter.

The invention consists in the combinations and arrangements of parts hereinafter described and claimed.

The invention will be best understood by reference to the accompanying drawings forming a part of this specification, and in which,

Fig. 1 is a top plan view of the invention;

Fig. 2 is a side elevation of the invention;

Fig. 3 is a fragmentary side elevation of the invention viewing the same from the side opposite to that shown in Fig. 2, the operating levers being shown in their normal closed position in full lines, and in their spread position in dotted lines;

Fig. 4 is a view partially in section on the line 4—4 of Fig. 1, parts of the device being broken away to more clearly disclose the arrangement of the same;

Fig. 5 is an enlarged sectional view on the line 5—5 of Fig. 1, showing the arrangement of the means for heating the rollers;

Fig. 6 is a view partly in section on the line 6—6 of Fig. 5; and

Fig. 7 is a sectional view on the line 7—7 of Fig. 4.

Referring to the drawings, 8 and 9 represent oppositely disposed curved levers pivotally connected together at 10, the lever 8 being provided with a handle 8'. Pivotally connected to the outer end of the lever 8, as shown at 13, is a guide member 14, which guide member is provided with an open slot 15 at its outer end. Pivotally mounted adjacent the outer end of the lever 9 as shown at 16, is a guide member 17 having turned portions 18 adapted to fit over the side edges of the guide member 14, so that the members 14 and 17 are mounted for sliding movement with respect to each other when the levers 8 and 9 are operated. Guide member 14 is provided with a stud 19, or other suitable anchoring means, and the guide member 17 is provided with a stud 20 or other anchoring means, and resilient means, shown in the form of a spring 21, has its ends connected with the studs 19 and 20, so that the levers are normally urged to closed position, the closing movement of said levers under the influence of the spring 21 being limited by means of a stud 20 upon the guide member 14 which engages a cut out portion 21' on the guide member 17 so as to check such closing movement. Mounted on the guide 17 is a shaft 22, and mounted upon the guide 14 is a shaft 23, and rotatably mounted upon the shafts 22 and 23 are rollers 24 and 25 respectively. The roller 24 is provided with a plurality of radially extending longitudinally disposed undulations or ribs 26, and the ribs 26 are preferably hollow as shown in Fig. 6. The inner end of the roller 24 is closed by means of insulating material 27, which fills the ends of ribs 26, and provides a bearing of insulating material for the inner end of the roller 24, the outer end of the roller preferably being closed by the material of which the roller is made, except for an aperture providing a bearing for engagement with the shaft, a washer 27 preferably being placed on the outer end of the shaft, together with a nut 28 to hold the washer and roller in position on the shaft. The roller 25 is identical to roller 24 as described, so that I will employ the same numerals to designate similar parts of such

rollers; however, it is here noted that the ribs 26 of the rollers 24 and 25, intermesh, and such rollers are normally held in meshing position by means of the spring 21, and 5 when the levers 8 and 9 are spread, the rollers 24 and 25 are spaced apart.

Embedded in the insulating material 27 and spaced and insulated from the shaft 22 is a metallic ring 29, and connected to said 10 ring is one end 30 of a heating coil 31, the opposite end 32 of the heating coil 31 being connected to a larger ring 33, embedded in the insulating material 27, so as to be insulated from the ring 29, the insulating material 15 between the ring 29 and the shaft, and between the ring 29 and the ring 33, extending outwardly so as to form annular grooves at the bottoms of which lie the rings 29 and 33. Mounted upon the guide member 17 is a 20 housing of insulating material 34 into which the ends 35 of the wires 36 extend, the ends 35 in each instance consisting of an enlarged metallic head 37, which forms a bearing for a spring 38, the inner end of which abuts 25 against a collar 39 secured to a contact plunger 40, which extends through the guide member 17, and into engagement with the ring 29, the contact 33' in the housing 34 being identical in construction and adapted to 30 engage the ring 33, all of which features are clearly shown in Figs. 4, 5, 6 and 7. A housing 41 on the guide member 14, similar to the housing 34, contains all of the parts described for the housing 34, which parts 35 energize the heating coil in the roller 25.

Preferably fixed upon the insulating material 27 at the inner end of the roller 24 is a ratchet wheel 42, and mounted on the guide 17 is a pawl 43 held in engaging position with the 40 ratchet wheel 42 by a spring 44 so as to prevent retrograde movement of the ratchet wheel, and the roller with which it is connected. Pivotaly mounted upon the outer end of the lever 9 as shown at 45, is a handle 46, such handle having a laterally extending portion 47, to which is connected a link 48 the inner end of which is provided with a hooked portion 49 which is adapted to engage the teeth of the ratchet wheel 42, 50 there being a bracket 50 which engages the end of the link 48 to assure such engagement. A spring 51 is connected to the link 48 and to the lever 9 which serves to normally return the link 48 and the handle 46 to non-engaging position. The outer end of the 55 lever 9 is provided with a stop 52 which is adapted to limit the movement of the handle 46 and the link 48.

A housing 53 is disposed about the roller 60 25 so as to practically cover the same and thereby prevent inadvertent contact with the hot roller when the implement is in use, and a guard member 54 is disposed adjacent to the inner ends of the rollers to prevent the 65 hair coming in contact with the operating

parts of the device. A comb 55 is preferably provided on the inner sides of the rollers and is shown as held in position by arms 56 secured to the shaft 23, and to the guide member 14.

In operation the handles 8' and 46 are pressed together in such a manner as to overcome the tension of the spring 21, this movement serving to spread the rollers apart a suitable distance so that a strand of hair may be disposed therebetween and spread along the lengths of the rollers by means of the comb 55, the guard 54 preventing the hair from coming in contact with the moving parts of the device. When pressure upon the handles 8' and 46 is released the hair is held between the rollers, and operation of the handle 46 in such manner that the force employed does not overcome the tension of the spring 21, will impart a step-by-step movement to the roller 24, and consequently to the roller 25, through the movement of the hooked portion 49 and the link portion 48, such hooked portion engaging the ratchet wheel 42 and upon each successive pressure of the handle 46 serving to turn said ratchet wheel one notch, the pawl 43 preventing retrograde movement of the ratchet wheel.

Electrical energy is furnished the heating coils in the rollers while the rollers are turning, through the medium of the resilient contacts 40 which remain in constant engagement with the rings 29 and 33, and it is pointed out that by mounting the contacts upon the guide members 14 and 17, the contacts are not affected by the complete spreading of the rollers.

The invention is simple in construction, positive in operation and requires a minimum of manipulation in order to impart 105 an attractive wavy appearance to the hair.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 110 the appended claims.

Having described my invention what I claim as new and desire to secure by Letters Patent is:

1. A hair curling device of the character 120 described including supporting handles and rollers having undulating surfaces, said rollers being arranged to operate upon opposite sides of a strand of hair, and means connected to one of said handles for imparting a step by step movement to said rollers, substantially as described.

2. A hair curling device of the character 125 described including pivotally connected levers provided with rollers having undu-

lating surfaces, said rollers being arranged to operate upon opposite sides of a strand of hair, yieldable means normally pressing said rollers together, and means operable by 5 drawing together the handles of said levers for rotating said rollers and also for separating said rollers, substantially as described.

3. A hair curling device of the character 10 described including rollers having undulating surfaces, said rollers being arranged to operate upon opposite sides of a strand of hair, and levers with means including the handle parts of said levers for operating 15 said rollers, said operating means being arranged so that a slight pressure applied thereto will impart a step-by-step movement to said rollers while a greater pressure applied to said operating means will move said 20 rollers apart, substantially as described.

4. A hair curling device of the character described including rollers having undulating surfaces, said rollers being arranged to operate upon opposite sides of a strand of 25 hair, supporting handles with means thereon for imparting a step-by-step movement to said rollers and means to maintain uniform distribution of said strand of hair over said rollers, substantially as described.

30 5. A hair curling device of the character described including levers pivotally connected together; a guide member mounted adjacent the end of one of said levers, and a cooperating guide member mounted adjacent the end of the other of said levers, said members having slideable, interengaging 35 guide flanges and a roller mounted on each of said guide members, substantially as described.

40 6. A hair curling device of the character described including levers pivotally connected together, a guide member pivotally mounted adjacent the end of one of said levers, and a co-operating guide member 45 pivotally mounted adjacent the end of the other of said levers and having slideable connection with the first guide member; a roller mounted on each of said guide members; and yieldable means normally urging the 50 ends of said levers with said rollers together, substantially as described.

7. A hair curling device of the character 55 described including levers pivotally connected together; a roller associated with the end of each of said levers; yieldable means normally urging said rollers together; and ratchet mechanism connected to the handle of one of said levers, so that by application of a small degree of force to said handle, 60 said ratchet imparts a step-by-step movement to said rollers, while the application of greater force to said handle causes said rollers to move apart, substantially as described.

8. A hair curling device of the character 65 described including a hollow roller, a heat-

ing element mounted in said roller; insulating material mounted in the end of said roller, there being separate annular contacts in said insulating material connected to opposite ends of said heating element; and a 70 source of electrical energy having contacts engaging said annular contacts, substantially as described.

9. A hair curling device of the character 75 described including a hollow roller, a heating element mounted in said roller; insulating material mounted in the end of said roller, there being separate continuous contacts in said insulating material connected to opposite ends of said heating element; a 80 source of electrical energy having contacts engaging said continuous contacts; and means for yieldably holding said contacts in operative position, substantially as described. 85

10. A hair curling device of the character described including levers pivotally connected together; a guide member secured adjacent the end of one of said levers, and a cooperating guide member secured adjacent 90 the end of the other of said levers and having slideable connection with the first member; a roller mounted on each of said guide members; heating elements in said rollers; and a contact mounted on each of said guide members for delivering current to its related roller, substantially as described. 95

11. A hair curling device of the character described including pivotally mounted levers; a guide member adjacent the end of one 100 of said levers, and a cooperating guide member mounted adjacent the end of the other of said levers; a roller mounted on each of said guide members; yieldable means for normally holding said rollers in operative 105 position; means for operating said rollers, application of a slight pressure to said operating means imparting a step-by-step movement to said rollers, and the application of a greater force to said operating means 110 serving to move said rollers apart; heating elements in said rollers; and a contact mounted in each of said guide members and adapted to furnish current to said heating 115 elements in all positions of said rollers and said operating means, substantially as described.

12. A hair curling device of the character described including pivotally mounted levers; cooperating guide members mounted adjacent the ends of each of said levers; a shaft on each of said guide members; a roller mounted on each of said shafts, said rollers having intermeshing ribs; yieldable means for holding said rollers in mesh; heating elements in said rollers; an insulating member closing the end of each of said members, said insulating member being provided with spaced rings connected to the opposite end of the heating element; con- 125

5 contacts mounted on each of said guide members adapted to engage said rings; a ratchet wheel mounted on said insulating member; and a member pivotally mounted on the handle of one of said levers and having a portion adapted to operate said ratchet wheel, substantially as described.

In testimony whereof I have signed my name to this specification in the presence of two subscribing witnesses.

HULDA E. MIKAELSON.
